UNITED STATES PATENT OFFICE.

CHARLES H. FAWCETT, OF INDEPENDENCE, IOWA, ASSIGNOR TO INTERSTATE EVER-LICENSE COMPANY, OF INDEPENDENCE, IOWA, A CORPORATION OF IOWA.

LICENSE-HOLDING DEVICE.

1,330,068.

Specification of Letters Patent. Patented Feb. 10, 1920.

Application filed May 16, 1919. Serial No. 297,647.

To all whom it may concern:

Be it known that I, CHARLES H. FAWCETT, a citizen of the United States of America, and a resident of Independence, Buchanan county, Iowa, have invented certain new and useful Improvements in License-Holding Devices, of which the following is a specification.

My invention relates to improvements in license holding devices, and the object of my improvement is to supply in a license holding box or closed container therefor, means within the box for releasably securing the license card therein, and also supplying an instrument adapted for insertion into the box to release said securing means after mutilating the card, and also operable to eject the card from the holder.

This object I have accomplished by the means which are hereinafter described and claimed, and which are illustrated in the accompanying drawings, in which Figures 1 and 2 are top plan views of the box containing a license card, Fig. 2 showing the card holder released and partially withdrawn from the box by the operation of an instrument of special construction, parts in both figures being broken away; Fig. 3 is an under plan view of said box and its contents as detached from the base-plate; Fig. 4 is a top plan view of the card-holder as removed from the box; Fig. 5 is a longitudinal vertical section of said box and its contents, taken on the broken line 5—5 of Fig. 3; Fig. 6 is a transverse vertical section of the same, taken on the broken line 6—6 of said Fig. 3; Fig. 7 is an end elevation of the box as removed from its base-plate, and Fig. 8 is a perspective detail view of the instrument employed to mutilate the license card, release and propel the same from the box.

Similar numerals of reference denote corresponding parts throughout the several views.

The numeral 5 denotes a license card, such as may be used for the licensing of a vehicle, and is made of lacerable material, such as paper or thin cardboard. A closed box 50 composed of a casing 1, whose open top is closed by a plate of glass 4 supported on interior shelves 16, has horizontally flanged parts 2 receivable under folded-over parts 20 of a base-plate 21, said folded-over parts

being permanently brazed or secured upon 55 said flanges and both having perforations 3 to receive bolts to secure the device to a vehicle.

One end of the box 1 has a longitudinal slot through which the card-holder 15 may 60 be passed from without into the box. The license card 5 is fitted within the upraised flanges of said holder before the latter is placed in the box. Across the open bottom of the box is fixed a medial transverse bar 65 13 held in spaced end sockets 14. Between said sockets, a longitudinally directed bar-spring 12 is medially mounted on the bar 13 with its numbers concave upwardly to bear at their extremities upon opposite end parts 70 of the bottom of the holder 15, thus resiliently supporting the latter and preventing rattling or play of same within the box. One member of said spring is somewhat shorter than the other to leave space next 75 the end thereof on the bottom of the holder for a stop-plate 11 which is fixed to the holder, and which is engaged by that end of the spring when the holder is completely within the box. This prevents removal of 80 the holder from the box.

I have provided means for insertion into said box through a keyhole 9 in the opposite end of the box from the said slot, said key-hole being ordinarily covered by a movable 85 shield 10.

The card-holder 15 is provided with a medial longitudinal slot 6 near one end, the walls of said slot at opposite ends and sides thereof being offset to provide the rectangular notches 7 and 8 respectively. This slot 6 is under and parallel with the axis prolonged inwardly of the keyhole 9 or the cylindrical shaft 17 of an instrument 18 when the latter is inserted through said 90 keyhole. For purposes of convenience, it will hereinafter be denominated the key 18. This key has a terminal ward 19, preferably provided with one sharpened edge for a 95 purpose to be described.

When said key has been inserted into the box its full length above the card 5, and with its ward 7 rotated a quarter revolution, the ward is forced through the card and downwardly through the notch 7 to a vertical position in which it engages and depresses the adjacent member of said spring 12, releasing it from the stop 11. The key 105

is then pulled outwardly until its ward arrives at the opposite end of said slot, in its course the sharpened edge of the ward lacerating and mutilating the card 5 as indicated in said Fig. 2. The key is then rocked in the same direction enough to cause its ward to enter and engage the other notch 8, and as the spring-member is disengaged from the stop 11, the key may be pushed back inwardly into the box as shown in said Fig. 2, pushing the card holder partly out of the box. The key may then be withdrawn as it has some play within the box. The mutilated card is then removed from the holder, having been rendered incapable of further use or alteration.

This device is simple and easily operated, and effectively prevents illicit alteration and re-use of a license card after the expiration 20 of the term of said card.

Having described my invention, what I claim as new, and desire to secure by Letters Patent, is:

1. In combination, a box, a card-holder 25 therein, a lacerable card in said holder, and a device insertible in said boxing slidably and rockingly, and adapted after insertion, when rocked and moved slidingly, to lacerate said card.

2. In combination, a slotted box, a card-holder movable through said box and its slot, a lacerable card in said holder, and a device insertible in said boxing, and movable therein, adapted when rocked and then moved longitudinally in one direction to lacerate the card, and at the limit of the latter movement movable to engage said holder to propel the latter through said slot when moved longitudinally in an opposite direction.

3. In combination, a box having a slot in one end and an orifice in its opposite end, a card-holder movable through said slot and box, a lacerable card removably mounted in said card-holder, releasable locking-means in said box for locking said card-holder when within the box, and a device insertible through said box orifice and having engaging-means adapted, when the device is appropriately manipulated, to successively first lacerate the card, second, engage and release the locking-means from the card-holder, and third, to push the card-holder outwardly through said slot.

4. In combination, a box having a slot in one end and an orifice in its opposite end, a card-holder movable through said slot and box, a lacerable card removably mounted in said card-holder, releasable resiliently-controlled locking-means in said box for locking the card-holder in one position, and a device insertible through said orifice and adapted when manipulated appropriately, to successively first lacerate said card, second, engage said card-holder and simultane-

ously engage and release said locking-means, and third, propel the card-holder through said slot.

5. In combination, a box having a slot in one end and an orifice in its opposite end, a card-holder movable through said slot and box, a lacerable card removably mounted in said card-holder, a resilient catch in said box adapted to engage and lock said holder in one position, said holder having a projection, said resilient element engaging said projection, and a key-shaped instrument insertible into the boxing through said orifice, said instrument having a ward provided with a cutting edge, the instrument when so inserted, turned and then shifted back, lacerating said card with its ward, and engaging and releasing said catch, the instrument when rocked farther in the same direction, engaging said card-holder, and when pushed again into the box propelling the card-holder through said slot.

6. In combination, a box having a slot in one end and an orifice in its opposite end, a card-holder insertible through said slot into the box, a lacerable card removably mounted in said card-holder, said card-holder having an L-shaped slot beneath said card, a key-shaped instrument insertible through said orifice, adapted when turned, to puncture the card with its ward, the ward entering the L-part of the slot and then movable longitudinally of the slot when the instrument is moved outwardly to longitudinally lacerate the card.

7. In combination, a box having a slot in one end and an orifice in its opposite end, a card-holder insertible through said slot into the box, a lacerable card removably mounted in said card-holder, said card-holder having a slot beneath said card, the slot being straight, alined longitudinally with said orifice and its wall indented in two places, a key-shaped instrument insertible through said orifice into the boxing above the card longitudinally over said slot, having a sharpened ward which, when the instrument is turned, moved longitudinally outwardly, again turned, and moved longitudinally inwardly to pass into one of the indentations, will traverse the slot, lacerate the card, engage the other indentation, and then propel the card-holder in one direction.

8. In combination, a box having a slot in one end and an orifice in its opposite end, a card-holder insertible through said slot into the box, a lacerable card removably mounted in said card-holder, said card-holder having a slot beneath the card with wall-notches, an instrument insertible through said orifice having a part protrusible into a notch of said slot when turned to puncture and lacerate the card, a stop fixed on said card-holder adjacent to the slot, and a resilient catch under said slot releasably engaged

with said stop, said instrument when farther moved, being adapted to engage and release the catch from said stop while engaging another notch of said slot, the instrument then being operable to propel the card-holder in one direction.

9. In combination, a box, an orificed card-holder slidably mounted therein and withdrawable therefrom and having a stop-projection abutting upon its orifice, a plate-spring fixed in said boxing with one end releasably contacting with the card-holder to exercise tension thereupon in one direction and also engaged with said stop-projection 10 to lock the card-holder when within the box, and means insertible through the orifice of said card-holder, movable relatively to the card-holder and said plate-spring to engage

and disengage the spring from said stop, permitting withdrawal of the card-holder 20 from the box.

10. In combination, a box, a lacerable card removably mounted therein, separable resiliently-controlled coengaged means for securing the card within the box, and a lacerating and releasing device adapted for different successive movements in the box relative to the card and said securing means, to be actuated to successively lacerate the card, 25 operate said securing means to release the card therefrom, and then propel the card 30 from the box.

Signed at Waterloo, Iowa, this 12th day of May, 1919.

CHARLES H. FAWCETT.
